INVENTOR.

Charles P. Wetmore

BY

Louis O. French

ATTORNEY.

UNITED STATES PATENT OFFICE.

CHARLES P. WETMORE, OF MILWAUKEE, WISCONSIN, ASSIGNOR TO WETMORE-GIBBONS CO., OF MILWAUKEE, WISCONSIN, A CORPORATION OF WISCONSIN.

PROCESS OF MAKING SPUDS.

Application filed December 8, 1923. Serial No. 679,396.

The invention relates to a method of making what are commonly known to the art as "spuds" for barrels, tanks, boilers, etc., such spuds being pipe fittings adapted to be secured, generally by welding, to the barrel, tank or other receptacle.

Heretofore spuds have been made by casting or forging but by such methods the surfaces become oxidized and welding of the spuds is, therefore, difficult and unsatisfactory. The object of this invention is to provide a method for making a spud from sheet metal, preferably sheet steel, by which the sheet metal is subjected to a series of cold-drawing or forming operations to form the finished product.

The invention further consists in the method and steps of the method herein-after described, and more particularly defined by claims at the conclusion hereof.

In the drawings: Fig. 1 is a side elevation view of a circular sheet metal blank; Fig. 2 is a sectional view of this blank after a forming operation; Fig. 3 is a sectional view of the blank in a die after another forming operation; Fig. 4 is a view similar to Fig. 3 after another forming operation; Fig. 5 is a view similar to Fig. 4 after another forming operation; Fig. 6 is a view similar to Fig. 5 after another forming operation. Fig. 7 is a view similar to Fig. 6 showing the finished blank; Fig. 8 is a sectional view through the finished spud in place on the wall of a receptacle.

Briefly, my method consists in drawing a flat sheet metal blank into a tube having walls as thick as or thicker than the original blank and projecting upwardly from a flanged base or attaching portion and then compressing the tube and forcing it outwardly so as to form a boss on the opposite side of the base and provide a flanged tube of standard dimensions which may be threaded and whose base or flange may be readily welded to the metal wall of a receptacle, such as a barrel, tank, boiler, etc.

I first punch from sheet metal, generally sheet steel, a circular blank 9. This blank is then formed into a cup-shaped member, preferably by successive treatment in suitable dies, more than one drawing operation being preferred. In the first drawing operation the blank 9 is formed into a

shallow cup-shaped member 10. In the next drawing operation the member 10 is drawn into a deeper cup of smaller diameter with flanged sides to form the member 11, shown in Fig. 3, between the fixed die block 12 and the movable die 13. In the next drawing operation the cup 11 is drawn into a deeper cup of smaller diameter and with a more pronounced flanging to form the member 14, shown in Fig. 3, between the fixed die block 15 and the movable die 16.

The cup 14 thus formed is next subjected to a forming and punching operation to form a tubular member 17 having a flaring end 18 between the fixed die 19 and a punching and forming die 20, as shown in Fig. 5.

The tubular member 17 is then placed on a ring-shaped die 21 with its flaring end 18 resting upon an annular recess 22 in the die 21 and its tubular end has another ring-shaped die 23 placed over it and thereafter a movable plunger die 24 and the die 23 are moved relative to the die 21 to bend the flaring end 18 of the tube 17 outwardly at right angles to the tube whose walls are thickened by the action of the shouldered plunger 24 to form a flanged tube member 25, shown in Fig. 6.

Thereafter the tube member 25 is placed on a ring-shaped die 26 with its flanged end resting in an annular recess 27 in said die, a ring-shaped die 28 is placed over the upwardly projecting tubular portion 29 of the member 25 and a shouldered movable plunger die 30, moving through the die 28 with its reduced end working in the tube 25 of the member 25, is moved down and its shoulder 31 engages the top of the tubular portion 29 and exerts pressure thereon to displace the metal of the tube member 25 to form the finished blank 32, shown in Fig. 7, in which it will be noted that the wall of the tube has been displaced from the position shown in Fig. 6 and that a boss 33 has been bent up from the tube and the flanged base 34.

The finished blank 32 is then tapped or threaded to form the finished spud 35 which is shown in Fig. 7 applied to the wall 36 of a tank or other receptacle by having its flange portion 34 welded thereto adjacent an opening 37 in said wall, the tube projecting

beyond the base, as at 38, to center the spud in the opening.

I aim, in the appended claims, to cover all modifications which do not depart from the spirit and scope of my invention.

What I claim as my invention is:

1. The method of forming spuds from sheet metal which consists in subjecting a flat sheet metal blank to a series of drawing operations to form a cup-shaped member, drawing and punching this cup-shaped member to form a flared-end tube, compressing and bending this flared-end tube to form a flanged tube whose tubular wall is thicker than the thickness of the original blank, then bodily displacing a tubular part of the flanged tube longitudinally so that portions of the tube project from opposite

sides of the flange to form the finished spud blank.

2. The method of forming spuds from sheet metal which consists in subjecting a flat sheet metal blank to a series of drawing operations to form a cup-shaped member, drawing and punching this cup-shaped member to form a flared-end tube, compressing and bending this flared-end tube to form a flanged tube whose tubular wall is thicker than the thickness of the original blank, and then forming the finished spud blank by moving this flanged tube longitudinally to displace a part of the metal tube and the flange to form an exterior boss.

In testimony whereof, I affix my signature.

CHARLES P. WETMORE.
